Primary Examiner — Ian Simmons*Assistant Examiner* — Rose Herzog(74) *Attorney, Agent, or Firm* — QuickPatents; Kevin Prince(57) **CLAIM**

The ornamental design for a bra, as shown and described.

DESCRIPTION

FIG. 1 is a front perspective view of a bra, showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a lace pattern and a bow depict portions of the bra that form no part of the claimed design. The remaining broken lines in the drawings represent stitching that does form part of the claimed design.
